ROTARY CASTING.

1,286,555.

Specification of Letters Patent.

Patented Dec. 3, 1918.

Application filed May 1, 1918. Serial No. 231,834.

To all whom it may concern:

Be it known that I, DIMITRI SENSAUD DE LAVAUD, a citizen of the United States of Brazil, and a resident of New York, in the county of New York and State of New York, have invented certain new and useful Improvements in Rotary Castings, of which the following is a specification.

This invention relates to the art of casting metal in horizontal rotary molds, as for instance those rotated at such high speeds as to utilize centrifugal force. By such means, as is already known, cast iron pipes, sleeves, piston rings and other annular articles may be cast rapidly and economically.

The object of the present invention is to improve the art by providing a novel method of and apparatus for permitting even an unskilled molder to control the thickness of a casting absolutely and with a nicety of precision hitherto thought impossible. By the thickness of the casting is meant the difference between the inside and outside diameters thereof. Of course the outside diameter of the casting is determined by the inside diameter of the mold. The inside diameter of the casting, and hence its thickness is dependent on the magnitude of the charge of molten metal delivered to the mold at each casting operation; but the attainment of uniformity in successive charges has been most difficult. As previously constructed, a complete casting machine of the rotary type has comprised, in addition to the rotating mold, a rotatable trough which when beyond the mold is filled with a charge of molten metal, and then, when the mold and trough are overlapped, is dumped to deliver the molten metal to the mold. If when the trough is set in charge receiving position the two side edges of the pouring slot are not in the same horizontal plane, as is often accidentally the case, the charge delivered to the trough, where the filling of the trough to the spill-point is relied on, will be deficient. If the two side edges of the pouring slot are in the same horizontal plane, the trough may not be deliberately filled with a definitely ascertained charge less than its maximum capacity, as is sometimes desirable.

According to the present invention, a definite pouring edge of the slot is selected as a spill-index, this edge is first preliminarily

adjusted, as by deliberately tilting the trough slightly or elevating the edge more or less relative to the axis of rotation of the trough, and the trough is thereafter given a charge of molten metal the level of which bears a definite relation to the horizontal plane containing said edge, preferably such that the level is attained when the metal begins to spill over said edge. Stop means may be and preferably are provided to predetermine that the trough, when returned to charge receiving position, will always be tilted or have such edge elevated to the proper extent. Adjusting devices are also preferably provided, which may be included as parts of said stop means, whereby the extent of tilt or edge elevation of the trough on each functioning of the stop means may be determined in advance. According to the preferred practice of the invention, then, not only may a single type of trough be employed for charges of various magnitudes, but an unskilful founder, after the adjusting devices have been set once by a supervisor or foreman, may fill and dump the trough repeatedly to cast a great number of articles all of the same thickness. With the stop means nicely adjustable, the trough interior need not be very precisely calculated and constructed; dependence being placed on the supervisor to ascertain by simple experiment the spill-point of each trough at maximum capacity and to set the adjusting device accordingly.

The invention will be more clearly understood from the following description, when taken in connection with the accompanying drawing showing two types of apparatus illustrative of the invention.

In this drawing,

Figure 1 is an end elevation, showing a trough untilted in charge receiving position, the supporting means in which the trough is journaled, and a stop-means including an adjusting device carried by said supporting means;

Fig. 2 is a side elevation of the parts of Fig. 1;

Fig. 3 is a view similar to Fig. 1, but showing the adjusting device set to hold the trough tilted in charge receiving position;

Fig. 4 is a side elevation of a modified form of apparatus, wherein the stop-means includes an adjusting device carried by the

trough and itself having an edge constituting a variable pouring edge for the trough, to be used as a spill-index; and

5 Fig. 5 is a section on the line 5—5 of Fig. 4.

Referring to the construction shown in Figs. 1, 2 and 3, the trough 6 is rotatable in bearings 7 and 7^a carried by a base 8.

10 The trough is provided with a handle 9, and a hollow charge receiving interior 10 having a pouring slot 11.

The center of rotation of the trough is indicated at 12.

15 The stop-means comprises a fixed device or stop member 13, secured on the exterior of the trough near its bottom, and an adjusting device or stop member 14 here constituted as a screw threaded through a boss 15 and spirally adjustable transverse to the 20 trough opposite the device 13.

According to this arrangement, the spill-index edge of the pouring slot 11 is the side edge 11^a.

25 In operation, the supervisor first adjusts the stop member 13 so that with the two stop members functioning, that is, abutting, the opposite side edges of the pouring slot 11 are contained in the same horizontal plane and therefore the trough is in the position 30 of maximum capacity. A carefully measured charge of molten metal, exactly corresponding to the charge required to cast each of a series of articles of the desired thickness, is delivered to the trough. The stop 35 member 13 is then readjusted very carefully while the handle 9 is correspondingly moved to maintain the two stop members in abutment, until the spill point is reached or approached to the desired degree, say until the 40 parts are arranged as shown in Fig. 3. The trough is then turned over to the molder, and it is his duty merely to return the trough to the position shown in Fig. 3 each time before delivering molten metal thereto, 45 and then to fill the trough until a spill of the metal over the edge 11^a occurs or is imminent as just described. It will be seen from the construction shown that the molder may move the trough only in the direction D to 50 dump the trough and only in the direction R to return the trough to charge receiving position. In the present case the metal dumped from the trough into the mold is spilled over the same side edge (the side edge 11^a of the pouring slot) which acted as 55 the spill-index.

Referring to the construction shown in Figs. 4 and 5, the trough is of the same construction as before, except that opposite the 60 charge receiving interior of the trough the exterior thereof is provided with a plane-surfaced boss 16 surrounding a vertical slot 17 cut through the side of the trough and opening at its top into the pouring slot 11.

The stop-means comprises a fixed device or stop member 18, formed as an offset lug on the bearing 7^a, and an adjusting device or stop member 19 here constituted as a plate 70 slidable over the plane surface of the boss 16 opposite the vertical slot 17 and the stop member 18. The upper edge 19^a of the stop member 19 forms a variable pouring edge for the trough to be used as a spill-index. The stop member 19 is slotted as shown at 75 19^b, with the slot taking about the shank of a set-screw 20 threaded into the boss 16, so that the edge 19^a may be adjusted and secured at various distances below the adjacent side edge of the main pouring slot of 80 the trough. In order to facilitate such adjustment and securement, the boss 16 has a vertically elongated ear 21 vertically offset therefrom to coact with and align the adjacent edge of stop member 19. 85

In operation, the supervisor first adjusts the stop member 19 so that the edge 19^a thereof is opposite the adjacent side edge of the pouring slot of the trough, seeing to it that the stop members are in abutment, and 90 consequently that the opposite side edges of the pouring slot of the trough are in the same horizontal plane and the trough is in the position of maximum capacity. A carefully measured charge of molten metal, exactly corresponding to the charge required to cast each of a series of articles of the desired thickness, is delivered to the trough. Stop member 19 is then readjusted very 95 carefully until the spill point is reached or approached to the desired degree. The trough is then turned over to the founder, and it is his duty merely to return the trough to the position shown in Fig. 5 each time before delivering molten metal thereto, 100 and then to fill the trough until a spill of the metal over the edge 19^a occurs or is imminent as just described. It will be seen from the construction shown that the molder may move the trough only in the direction D to dump the trough and only in the direction R to return the trough to charge receiving position. In the present case the metal dumped from the trough into the mold is spilled over the side edge of the 110 trough on the opposite side of the trough from the side utilized for the spill-index. 115

In carrying out the process of the invention, therefore, according to either of the 120 illustrative embodiments of the apparatus facilitating the same and coming within the invention, first, a pouring edge of the trough (as the edge 11^a, Fig. 2, or the edge 19^a, Fig. 4) is selected as the spill-index next the position of said edge is adjusted 125 relative to the axis of rotation of the trough to set said edge as a spill-index relative to the desired magnitude of charge, and next the trough is filled so that the liquid level of the molten metal therein bears a definite 130

relation to said edge as thus adjusted and positioned, before dumping the trough to discharge the charge therein into the mold.

I claim:

5. 1. The method of predetermining the magnitude of the charge of molten metal deliverable by a rotatable trough to the rotating mold of a rotary casting machine, where the trough is provided with a pouring 65 slot having a pouring edge adapted to serve as a spill-index relative to a predetermined magnitude of charge, which comprises preliminarily adjusting the position of said edge relative to the axis of rotation of the 70 trough to constitute said edge as a spill-index relative to the desired magnitude of charge, then filling the trough so that the liquid level of the molten metal therein bears a definite relation to said edge 75 15 as thus positioned, then arranging the trough and mold in overlapping relation, and then dumping the trough to spill the charge out of the trough into the mold. 20
2. The method of predetermining the magnitude of the charge of molten metal deliverable by a rotatable trough to the rotating mold of a rotary casting machine, where the trough is provided with a pouring slot having at least one side edge parallel 80 to the axis of rotation of the trough, which comprises preliminarily adjusting the trough relative to its axis of rotation to set said edge as a spill-index indicative of the quantity of molten metal which may be accommodated between the horizontal plane 85 containing said edge and the wall area of the trough interior below said plane, then filling the trough to the spill point, then arranging the trough and mold in overlapping relation, and then dumping the trough to spill the charge out of the trough into the mold. 90
3. The method of predetermining the magnitude of the charge of molten metal deliverable by a rotatable trough to the rotating mold of a rotary casting machine, where the trough is provided with a pouring slot having at least one side edge parallel to the axis of rotation of the trough, which comprises preliminarily adjusting the trough 95 relative to its axis of rotation to set said edge as a spill-index indicative of the quantity of molten metal which may be accommodated between the horizontal plane 100 containing said edge and the wall area of the trough interior below said plane, then filling the trough so that the liquid level of the molten metal therein bears a definite relation to said plane, then arranging the trough and mold in overlapping relation, and then dumping the trough to spill the charge out of the trough over said edge into the mold. 105
4. The method of predetermining the magnitude of the charge of molten metal deliverable by a rotatable trough to the rotating mold of a rotary casting machine, where the trough is provided with a pouring slot having at least one side edge parallel to the axis of rotation of the trough, which comprises preliminarily tilting the trough to predetermine set said edge to act as a spill-index relative to the attainment of a charge, by the trough less than the maximum capacity of the trough, then delivering 110 molten metal to the trough until said spill-index functions, and thereafter dumping the trough to discharge into the mold all the molten metal in the trough. 115
5. In a rotary casting machine, in combination, a pouring trough provided with a pouring slot having a spill-index edge, stop means for preventing disposition of the trough to arrange said edge to lower the capacity of the trough for containing molten 120 metal below a predetermined minimum, and means for rotating the trough about its axis from such disposition to dump the trough. 125
6. In a rotary casting machine, in combination, a pouring trough provided with a pouring slot having at least one side edge parallel to the axis of rotation of the trough, stop means for preventing disposition of the trough to arrange said edge to lower the capacity of the trough for containing molten metal below a predetermined minimum, and means for rotating the trough about its axis to dump the charge in the trough into the mold over said edge. 130
7. In a rotary casting machine, in combination, a pouring trough provided with a pouring slot having a spill-index edge, supporting means for the trough during rotation, co-acting parts carried by the trough 135 and by said means for preventing disposition of the trough to arrange said edge other than in a predetermined location, and means for variously adjusting the relation of said co-acting parts whereby on arranging the trough in charge receiving position said edge is always located at one of several levels relative to the axis of rotation of the trough. 140
8. In a rotary casting machine, in combination, a rotary pouring trough, supporting means for the trough, a stop-member carried by the trough and having a definite location relative to a selected pouring edge of the trough, and a co-acting stop-member carried by said means, one of said parts being preliminarily adjustable to predetermine that when the stop-members are in abutting relation said selected pouring edge constitutes a spill-index to facilitate always filling 145 the trough to a predetermined extent. 150

9. In a rotary casting machine, a construction as described in claim 8, wherein the stop-member on the trough is fixedly offset from the exterior thereof, and the stop-member on said means is adjustable from or toward the other stop-member thereby to partially tilt the trough to set the

same for accommodating to the verge of spill a charge of molten metal less than the maximum capacity of the trough.

10

Signed at New York, in the county of New York and State of New York this 26th day of April A. D. 1918.

DIMITRI SENSAUD DE LAVAUD.
